WRINGER RELEASE MECHANISM

Oscar T. Anderson, Waterloo, Iowa

Application October 3, 1938, Serial No. 232,915

6 Claims. (Cl. 68—263)

This invention relates to clothes wringers, and more particularly to an improved wringer pressure release and reset mechanism.

The primary object of the invention is to provide a wringer of such design and construction that no mechanical parts of the wringer are subject to extreme or violent movement sufficient to injure or endanger the operator when the release control is actuated.

Another important object is to provide a wringer release mechanism of extreme simplicity whereby relatively great operating pressure between the wringer rolls may be positively released by a minimum manual effort.

A further object is to provide a rugged and dependable wringer release and reset mechanism of extreme simplicity of mechanical design and adapted to unusually economical manufacture.

These and other important objects are accomplished by the peculiar construction, arrangement and combination of parts, as hereinafter set forth, and which are here illustrated in connection with a preferred embodiment of the invention as illustrated in the drawings attached hereto and forming a part of this specification.

Referring now more particularly to the drawings,

Fig. 1 is a side elevation of a wringer constructed in accordance with the principles of this invention, certain parts being shown broken away to more clearly illustrate the internal wringer mechanism.

Fig. 2 is a fragmental sectional view of the release mechanism; the several parts being illustrated in the positions they assume at the instant of release.

Fig. 3 is a fragmental sectional view similar to Fig. 2, but illustrating the several parts in the position they assume during the resetting operation.

Fig. 4 is a detail perspective view of the resetting link.

Fig. 5 is a detail perspective view of the reset lever bracket.

The general wringer construction

The typical wringer construction illustrated in the drawings includes a wringer frame comprising a bottom channel 11 extending longitudinally of the wringer and secured at each of its ends by welding or otherwise to one of the vertical end channel members 12 and 13. Each of these end channels is so formed as to provide a vertical slideway for suitable bearing members supporting a resilient upper wringer roll 14, and a simi-

lar lower wringer roll 15, and by reference to Fig. 1 it will be seen that the bearings 16 and 17 in which the shaft 18 of the lower roll 15 is journaled are limited in their downward movement within the channels 12 and 13 by the upwardly extending bearing support portions 19 formed at each end of the bottom channel 11.

This construction provides means for maintaining the lower roll 15 in a fixed axis at all times, since the downward movement of the bearings 16 and 17 is definitely limited by the supports 19, and upward movement is prevented by the spring pressure as exerted downwardly by the upper roll 14.

The rolls are rotatably driven by any suitable power source which is preferably coupled to the shaft 18 of the lower roll 15 by power transmission mechanism enclosed in any desirable type of power head 21. The housing of the power head 21 carries the entire wringer frame by means of the brackets 22 formed on the end channel 12 and secured to the power head by cap screws 24.

The shaft 25 of the upper roll 14 is journaled for rotation in the bearing members 26 and 27, and this roll is urged downwardly into resilient engagement with the lower roll 15 by means of the flat leaf type pressure spring 28 adjustably mounted on the top channel 29 by means of an adjustment screw 31 which is threaded into the bushing 32 and which is operatively secured to the center point of the spring 28 by a retaining clip 33. The retaining clip 33 is secured to the spring 28 and engages the reduced portion 34 of the adjustment screw 31 in order that the screw 31 and spring 28 will be in operative engagement at all times, and the end portions of the spring 28 directly engage and exert a downward pressure on the bearings 26 and 27 to provide suitable operating pressure between the two rolls.

The release and reset

In the present invention the operating pressure effective between the rolls 14 and 15 is released by releasing the top channel 29 from the wringer frame, and is reset by returning the top channel to the operating position illustrated in Fig. 1, and it should, therefore, be pointed out that the essence of this invention resides in the new, improved and simplified mechanism for accomplishing this purpose.

One end of the top channel 29 is secured to the upper end of the vertical channel 12 by a hook connection 41 formed by striking a lip 42 outwardly from the channel 12 in such a manner that it may be releasably engaged by the lower

edge 43 of an orifice formed similarly in the end wall 44 of the top channel 29.

Means for securing the opposite end of the top channel 29 to the vertical channel 13 include a reset lever bracket 45 which may be welded or otherwise suitably secured to the channel 13, a resetting lever 46 pivoted thereon by means of the rivet 47, a resetting link 48 pivotally mounted on the lever 46 by means of the rivet 49, and a latch pin 51 projecting upwardly through a suitable orifice in the top wall 52 of the top channel 29 and engaging a latch orifice 53 in the resetting link 48.

Manual release of the wringer is accomplished by mounting the latch pin 51 on a release plate 54 which is loosely secured to the lower surface of the top wall of the top channel 29 by an anchor rivet 55, and which is so formed as to include a manual release button 56 projecting upwardly through a suitable orifice 57 in the top 29. The release plate 54 is normally urged upwardly by a spring 58 carried on a spring pilot 59 in order that the latch pin 51 will project through the latch orifice 53 in the resetting link 48 and lock the parts in the operating position illustrated in Fig. 1.

In this connection it should be observed that one advantage of this structure over those heretofore in use resides in the fact that the present locking means is not subject to accidental release such as has frequently been experienced in prior art devices whenever the operating pressure becomes unusually high. This feature is quite important, since it will be readily appreciated that this operating pressure varies not only with the adjustment of the screw 31, but also varies in accordance with the thicknesses of goods fed between the rolls 14 and 15.

The top channel 29 is subject to the full pressure exerted by the spring 28, but this force acts directly upwardly against the lower bearing surface 52 of the resetting link 48 in such a manner that while the angular position of the surface 52 will result in a definite camming action tending to pivot the link 48 in a clockwise direction about the rivet 49, yet this force is of far less magnitude than the force of the spring 28, and the latch pin 51 which engages the latch orifice 53 prevents any possibility of accidental release. At the same time, the force exerted on the latch pin 51 by the link 48 acts at right angles to the axis of the pin and, therefore, will not tend to cause it to release the latch orifice 53, irrespective of variations of the magnitude of the force.

To release the rolls, the operator may strike the release button 56, which will depress the release plate 54 and cause the latch pin 51 to be withdrawn from the orifice 53 in the link 48. As just pointed out, the magnitude of the force acting upon this latch pin 51 is very small and consequently insufficient to cause any appreciable resistance to the releasing movement of the pin. As the pin 51 releases the orifice 53, the link 48 will pivot outwardly in a clockwise direction until the bearing surface 52 disengages the top 29 and allows the top to spring upwardly sufficiently to release all tension on the pressure spring 28. A pair of slotted limit links 61 are mounted on rivets 62 and engage a cross pin 63 to prevent undue movement of the top 29 under extreme pressure conditions, and a limit pin 65 is likewise provided on the link 48 to engage a pair of stops 66 formed on the bracket 45 and limit the pivotal movement of the link 48.

To reset the mechanism, it is only necessary

that the operator reengage the hook connection 41 if it is disengaged, lift the resetting lever 46 sufficiently to engage the latch pin 51 with the orifice 53 (see Fig. 3) and force the reset lever

5 46 downwardly against the vertical channel 13 into the position shown in Fig. 1. As this is done the rivet 49 crosses the dead center position established by the latch pin 51 and the rivet 47, and the resetting lever 46 is thus secured in position without the necessity of any other locking means.

From the above description it should be apparent that by practicing the principles of this invention, a wringer of extreme simplicity and 15 rugged construction has been provided which not only possesses the obvious advantage of economy of manufacture, but also is of great merit in that its release mechanism is not subject to accidental release and is yet easily and positively released 20 by a very light manual touch; and also in that it is so designed that no parts are subject to such extreme or violent movement that they might strike and injure the operator when the release control is actuated.

25 While I have shown and described a preferred embodiment of this invention as required by the patent statutes, yet it is subject to numerous modifications and I, therefore, do not wish to be limited except as by the scope of the appended 30 claims.

I claim:

1. In a clothes wringer including a plurality of pressure rolls, a pressure spring, and a plurality of separable frame members normally urged apart under pressure exerted by said pressure spring, the combination of a manually operable reset mechanism interconnecting said separable frame members and adapted to force said frame members into operating position 40 against the force exerted by said pressure spring; said reset mechanism comprising an upright link normally effective to retain the frame members in operating position against the force exerted by the pressure spring, cam means responsive to the pressure exerted by said pressure spring for moving said link in a direction axially of said pressure rolls, and manually operated latch means for releasably retaining said link against said axial movement.

50 2. In a clothes wringer comprising a pair of pressure rolls, bearings for said rolls, and slide-ways adjacent each end of said rolls for carrying said bearings, the combination of a spring 55 extending between said bearing slide-ways and adapted to urge said bearings and rolls into operative position, a longitudinal frame member extending between said bearing slide-ways and supporting said pressure spring, means for releasably securing one end of said longitudinal frame member to one of said bearing slide-ways, a toggle release and resetting linkage whereby the opposite end of said longitudinal frame member may be forced into operating position 60 against the force exerted by said pressure spring; said release and reset linkage comprising a reset lever having an extension constituting a handle for manipulating said toggle linkage, a link pivotally connected at one end with said reset lever, and manually operated latch means 65 for releasably connecting said frame member with the opposite end of said link to retain the frame member in said operating position, with said opposite end of the link, on release of said link by said latch means, being movable in a direction of force exerted by said pressure spring.

3. In a clothes wringer comprising a pair of pressure rolls journaled for rotation in bearings mounted in slideways adjacent each end of said rolls, the combination of a pressure spring extending between said bearing slideways and adapted to urge said bearings and rolls into operative position, a longitudinal frame member extending between said bearing slideways and supporting said pressure spring, and a release and resetting linkage whereby the said longitudinal frame member may be forced into operating position against the force exerted by said pressure spring; said release and reset linkage comprising a reset lever, a link, and additional means for releasing said link without movement of said lever.

4. The combination, with a clothes wringer comprising a frame, a plurality of cooperating pressure rolls, a pressure spring, and a spring supporting member movable with respect to said frame, of a pressure release and reset mechanism extending between said frame and said spring supporting member and adapted to releasably secure said spring supporting member in operating position; said release and reset mechanism including a pivoted reset lever, a tension link, a latch carried on said supporting member releasably connectible with one end of said link, means pivotally connecting said reset lever with the opposite end of said link, said tension link being under tension when said spring supporting member is in said operating position, and manual means operating said latch for disconnection from said link to release said supporting member from said operating position, said link on release of said supporting member being without tension and pivotally movable on said reset lever relative to said supporting member.

5. In a clothes wringer including a plurality of pressure rolls, a pressure spring, a main frame, a top frame separable from said main frame and normally urged upward and apart from said main frame under pressure exerted by said pressure spring, the combination of a manually operable reset mechanism interconnecting said separable frame members and adapted to force said frame members into operating position against the force exerted by said pressure spring;

said reset mechanism comprising a reset lever, a reset link, a pivotal connection between said reset lever and said main frame, a pair of cam surfaces adapted to engage each other and comprise a pivotal connection between said link and said top frame, said cam surfaces being so formed that the force exerted by said pressure spring will result in a reduced force tending to move said cam surfaces out of engagement with each other; locking means to maintain said cam surfaces in engaged relationship, and release mechanism for said lock comprising a manually operable member independent of said reset lever whereby said locking means may be released to permit relative movement of said cam surfaces to a disengaged position to release said frame members for relative movement without imparting movement to said reset lever.

6. In a clothes wringer including a plurality of pressure rolls, a pressure spring, a main frame, a top frame separable from said main frame and normally urged upward and apart from said main frame under pressure exerted by said pressure spring, the combination of a manually operable reset mechanism interconnecting said separable frame members and adapted to force said frame members into operating position against the force exerted by said pressure spring; said reset mechanism comprising a reset lever, a reset link, a pivotal connection between said reset lever and one of said frame members, a pair of cam surfaces adapted to engage each other and comprise a pivotal connection between said link and one of said separable frame members, said cam surfaces being so formed that the force exerted by said pressure spring will result in a reduced force tending to move said cam surfaces out of engagement with each other, locking means to maintain said cam surfaces in engaged relationship, and release mechanism for said lock comprising a manually operable member independent of said reset lever whereby said locking means may be released to permit relative movement of said cam surfaces to a disengaged position to release said frame members for relative movement without imparting movement to said reset lever.

OSCAR T. ANDERSON.
